UNITED STATES PATENT OFFICE.

JOSEPH B. LEATHERBARROW, OF MANCHESTER, ENGLAND, ASSIGNOR OF
ONE-HALF TO THOMAS BUTLIN MARGETTS, OF TABLE CAPE, TASMANIA.

SHEAF-BINDING HARVESTER.

SPECIFICATION forming part of Letters Patent No. 683,609, dated October 1, 1901.

Application filed February 20, 1900. Serial No. 5,910. (No model.)

To all whom it may concern:

Be it known that I, JOSEPH BISPHAM LEATHERBARROW, a citizen of the United States of America, residing at Manchester, in the 5 county of Lancaster, England, have invented a new and useful Improved Sheaf-Binding Harvester, of which the following is a specification.

This invention relates to an improved construction of sheaf-binding harvesters, with the object of improving the means for bundling and tying the sheaves and dispensing with the packers.

For the purpose of more clearly describing the nature of my invention I have annexed hereunto three sheets of drawings. In the several views shown therein similar characters refer to similar parts.

Figure 1 is a side view showing my invention applied to any ordinary reaping-machine. Fig. 2 is a plan view with the needle and tying mechanism omitted. Fig. 3 is an end view also without the needle and tying mechanism and showing the rod controlling the 25 clutch for these mechanisms broken away and its guide omitted for the sake of clearness. Fig. 4 is an end view, Fig. 5 a side view, and Fig. 6 a plan, of a part of the machine showing the discharging-arms and 30 needle.

The improvement which forms the subject of this invention may be affixed to any reaping-machine, such as partly indicated at *a*, in which the grain after being cut falls onto 35 the platform and is carried up between canvas elevators *j*, that are supported on rollers *j*.

In this my invention the grain passes from the elevator and is received on a cradle that is formed of a row semicircular arms *b* when 40 they are in the position shown by dotted lines in Fig. 1, said arms being fixed to a cross-shaft *c*, extending from side to side of the frame *d* and supported in brackets *c'*. A lever *e* is fitted to one end of the shaft *c*. At the 45 inner end of this lever a balance-weight *f* or an equivalent is attached, and the opposite or outer end *e'* is connected by a rod *g* to a lever *k*, that is fitted on the end of a transverse shaft *l*, which is placed above the shaft *c* and 50 parallel thereto. A row of semicircular arms *q* are fitted on and depend from the shaft *l*,

which is pivoted in brackets, as *m*. The needle *p* is carried by a shaft *p'* in bearings on the frame *t*, so that when encircling the sheaf the back of the needle is outward and the 55 needle-eye *p'* inward, or the reverse of the ordinary position. Any preferred form of knotter may be employed for binding the sheaf. The binder attachments employed in combination with the mechanism hereinabove described may be such as shown or has been in use hitherto.

In the construction shown in the drawings, *a'* is the driving-wheel, from which power is transmitted to the binder attachments 60 through the sprocket-wheel *a'*, chain *d'*, shaft *a'*, bevel-wheels *d'*, shaft *a'*, sprocket-wheel *r* on the latter, and a chain to the sprocket-wheel *a'*, fast on the shaft *s*, which turns in the frame *t*. At the other end of this 65 shaft *s* is a sprocket-wheel *a'*, loose on the shaft, but adapted to be clutched thereto by a clutch *v'* when the latter is freed from the stop-bar *u*, pivoted to the frame *d*. When this bar is in the position indicated by the dotted lines in Fig. 1, the catch *v* of the clutch comes against the end *u'* of the bar and the 70 clutch is held back, so that the sprocket-wheel *a'* is held free on the shaft. When, however, the stop-bar *u* is raised to the position 75 shown by full lines in Fig. 1 and the clutch is thus released, the latter will clutch the wheel *a'* to the shaft and then by means of a chain will transmit rotary motion to the sprocket-wheel *a'*, fast on the crank-shaft *7*, 80 Figs. 1, 3, and 5. This shaft *7* has at its outer end a crank *10*, connected by a rod *11* to a crank-pin *p'* on the needle *p*. Another crank *12* on the shaft *7* is connected by a rod *13* to an arm *x'*, Figs. 4 and 5; on a shaft *x'*, 85 carrying a pair of discharge-arms *x*.

In working my invention the inner end of the lever *e*, with the weight *f*, will be in the position indicated by dotted lines in Fig. 1, which will cause the cradle *b* also to be in 95 the position so indicated. The lever *e*, whose downward movement is limited by a stop *e'* on the frame *d*, passes through a slot *s'* in the rod *s*, whose upper end works in a guide *s'*, and the lower end of said rod is connected 100 to the free end of the stop-bar *u*. The end *u'* engages with the catch *v* of the clutch

when the cradle *b* and the lever *e* are in the positions hereinbefore named and prevents action of the clutch. When a supply of grain has been deposited in the cradle *b* having sufficient weight to overcome the resistance of the weight *f* at the end of the lever *e*, the cradle *b* will be lowered to the position shown in full lines in Fig. 1 of the drawings. At the same time the opposite end *e'* of the lever *e* will cause the shaft *l* to rotate, and the guard *q* will be placed in proximity to the elevators, thereby temporarily preventing the grain passing onto the cradle *b*. The raising of the weighted end of the lever *e* with-
draws the end *u'* of the stop-bar *u* from the catch *v*, thereby permitting the sprocket-wheel *a⁵* to revolve with its shaft and so to actuate the sprocket-wheel *a⁶*, causing the needle *p* to encircle the sheaf, which is then fastened by the knotter, and the needle is withdrawn. Then the arms *x* discharge the sheaf from the cradle *b*, which then rises by the action of the weight *f* or equivalent, the guard *q* is lifted, the end *u'* of the stop-bar *u* engages with the catch *v*, stopping the motion of the sprocket-wheels *a⁵* and *a⁶*, and the operation hereinbefore described is repeated.

I claim as my invention—

1. A sheaf-binding harvester having an elevating means, a cradle pivoted below the discharge end thereof, a guard pivoted above, cranks and a connecting-rod between the cradle and guard, a lever and weight *f*, a

catch *u* and means to operate it from the cradle, in combination with binding devices 35 below the upper position of the cradle, clutch-gears and cranks to operate said devices when the catch *u* is operated, upon the cradle taking up a position below the receiving position, as and for the purpose described. 40

2. In a sheaf-binding harvester, an elevating means, a cradle at the discharge end of the elevating means, a guard *q*, lever and crank connections between the cradle and the guard whereby the guard is adapted to be 45 placed in position in front of the discharging means upon the withdrawal therefrom of the cradle for the purposes described, a catch operated by the withdrawal of the cradle and clutch mechanism controlled by the catch in 50 combination with a train of gears and cranks, a needle pivoted at *p'* and operated so that when the cradle is in its lowest position it will have its point inward, and a crank and rod connecting the needle to the gears, all 55 adapted to be operated after the cradle has left the discharge end of the elevator and at rest when it has returned thereto, as described.

In testimony whereof I have signed my name to this specification in the presence of two subscribing witnesses.

JOSEPH B. LEATHERBARROW.
